INVENTOR

Victor J. Evans

ATTORNEY

UNITED STATES PATENT OFFICE.

SIMEON LEDOUX, OF KANSAS CITY, MISSOURI.

FASTENER.

Application filed February 10, 1925. Serial No. 8,314.

To all whom it may concern:

Be it known that I, SIMEON LEDOUX, a citizen of the United States, residing at Kansas City, in the county of Jackson and 5 State of Missouri, have invented new and useful Improvements in Fasteners, of which the following is a specification.

This invention relates to fasteners and 10 contemplates the provision of means for locking the mouth of a mail bag so that the same cannot be opened during transit or storage.

Another object of the present invention is the position of a collar having a sleeve 15 received therein whereby a simple twist of the collar will force the sleeve up through the collar and firmly engage a tie rope upon each twist.

A further object of the invention is the 20 provision of means located upon the upper ends of the sleeve whereby when the same protrudes through the upper end of the collar the same may receive the yoke of a lock therein so that the sleeve cannot be unscrewed or disengaged from the collar.

With the above and other objects in view, the invention further includes the following 25 novel features and details of construction, to be hereinafter more fully described, illustrated in the accompanying drawings and pointed out in the appended claims.

In the drawings:

Figure 1 is a side elevation of a bag showing the invention applied.

Figure 2 is a longitudinal sectional view 30 taken through the fastener.

Figure 3 is a top plan view of the sleeve members.

Figure 4 is a bottom plan view.

Figure 5 is a perspective of one of the 40 sleeves.

Figure 6 is a detail view of one of the fastening cords.

Referring to the drawings in detail 45 wherein like characters of reference denote corresponding parts, the reference character 10 indicates a mail bag of the usual and wellknown construction and used in accordance with the present invention. It is well known that when filling or emptying bags 50 of this type, the cords will hold back small packages, newspapers and letters, which remain in the bag indefinitely.

In order to provide a very simple, cheaply 55 manufactured fastening means which is

simple in operation I provide a collar as shown at 11 having its lower end portion enlarged as at 12 and further having upon the inner sides of its enlarged portion a threaded portion 13 which extends within 60 the same an appreciable distance. Received within the collar 11 are substantially semi-circular sleeve members 14 also having their lower edges enlarged and threaded as at 15, and threadedly engaging portion 13 of 65 the collar 11. It will be noted that there are two of such sleeves and received within the inner edges thereof is a plurality of cords or ropes 16, and preferably four as shown in Figure 4 of the drawings. Thus 70 far, it will be noted that the ends of the cords 16 may extend above the top of the sleeves 14, an appreciable distance, and while holding the ends of the ropes or cords in one hand engaging the collar 11, and giving the same a downward pull it will be seen that the cord or rope 16 will force the sleeve 14 outwardly so that the enlarged threaded portion 15 of the sleeve 14 will engage the 75 threaded portion 13 of the collar 11 and travel upwardly therethrough. As the sleeves travel upwardly through the collar 11 it will be seen that due to the enlarged portion of the sleeves and collar that the sleeves will more firmly engage the ropes 80 or cords 16 upon each upward twist.

Made integral with and extending from the upper portions thereof upon the sleeve 14 are apertured ears 17 which are so arranged that both of the sleeves when extending through the collar 11, the apertured portion thereof will be in registration when the sleeves extend above the upper periphery of the collar 11 whereby the yoke of the lock 18 will be inserted therein in order to render the bag inaccessible to unauthorized persons. Secured to the ends of the rope or cord 16 are hooks and snaps 19 and 20 respectively, the hooks 19 adapted to be received within eyelets provided in the top of the bag, the snaps 20 preventing unravelling of the ends of the ropes or cords 16.

There is also provided upon one side of the collar 11 a spaced strip 21 which may be preferably spaced therefrom to receive 105 way tickets in order to determine the bag's destination.

The invention is susceptible of various changes in its form, proportions and minor details of construction and the right is here- 110

in reserved to make such changes as properly fall within the scope of the appended claims.

What is claimed is:—

- 5 1. A mail bag fastener of the character described comprising a hollow cylindrical member having its lower end enlarged and interiorly threaded, a pair of companion sleeve members having their lower ends enlarged and threadedly engaging the threaded portion of the cylindrical, registering apertured lugs extending from the upper ends of the companion sleeve members, fastening means extending therethrough to hold the guy ropes within the companion sleeve members and against accidental rotation of the companion sleeve members and held therein from accidental displacement.
- 10 2. A fastener for mail bags comprising a hollow cylindrical member having its lower end enlarged and interiorly thread-

ed, a pair of U-shaped companion sleeve members received within the hollow cylindrical member and adapted to travel upwardly through the hollow cylindrical member, guy ropes received within and extending through the sleeve members, registering apertured ears extending from the upper portion of the sleeve and adapted to receive a locking means therein.

3. A fastener for mail bags comprising a hollow cylindrical member having its lower end enlarged and interiorly threaded, a pair of flared exteriorly threaded sleeves adapted to be received within the hollow cylindrical member and adapted to be brought into threaded engagement therewith, and ropes extending from the bag through the sleeve members and engaging the inner side walls of the sleeve members.

In testimony whereof I affix my signature.

SIMEON LEDOUX.
